(57) **CLAIM**

The ornamental design for a multifunction infant carrier, as shown and described.

DESCRIPTION

FIG. 1 is a rear perspective view of the multifunction infant carrier of the present invention showing our new design; FIG. 2 is a front perspective view thereof; FIG. 3 is a top plan view thereof; FIG. 4 is a rear elevational view thereof; the broken line showing of surfaces of the belt carrier represents stitching, and forms part of the claimed design; FIG. 5 is a left side elevational view thereof, the right side elevational view being a mirror image thereof; FIG. 6 is a front elevational view thereof; and, FIG. 7 is a bottom plan view thereof.
